(57) **CLAIM**

The ornamental design for a sewer hose elbow cap, as shown and described.

DESCRIPTION

FIG. 1 is a top, front, right side perspective view of a sewer hose elbow cap showing our new design;

FIG. 2 is a bottom, rear, left side perspective view thereof;

FIG. 3 is a top plan view thereof;

FIG. 4 is a bottom plan view thereof; and,

FIG. 5 is a right side elevational view thereof, the left side elevational view, front elevational view, and rear elevational view all being a mirror image thereof.

1 Claim, 5 Drawing Sheets

FIG. 1

FIG. 2

FIG. 3

FIG. 4

FIG. 5
